RADIO TUBE REJUVENATOR

William Bartlett and Ralph Carpenter, Spencer,
W. Va., assignors of one-third to Wm. S. Ryan,
Spencer, W. Va.

Application April 23, 1936, Serial No. 76,967

6 Claims. (Cl. 250—27)

This invention relates to radio tubes or valves, and more particularly to a means for recovering or rejuvenating wornout tubes.

An object of this invention is to provide an exceedingly simple means whereby the thorium which has been driven off of the cathodes during the use of the tubes may be restored to the cathodes without unsealing the tubes.

Another object of this invention is to provide a tube rejuvenating means which may be used with various types of tubes, and by means of which the rejuvenating process is accomplished through the external application of heat.

A further object of this invention is to provide an improved method of rejuvenating tubes whereby the condition of the tubes can be determined during the process of rejuvenation.

With the foregoing and other objects in view, the invention will be more fully described hereinafter, and will be more particularly pointed out in the claims appended hereto.

In the drawings, wherein like symbols refer to like or corresponding parts throughout the several views:

25 Figure 1 is a detail front elevation of a tube rejuvenating device constructed according to an embodiment of this invention.

Figure 2 is a top plan of the device.

30 Figure 3 is a detail end elevation of the device.

Figure 4 is a detail end elevation, partly broken away and in section of the device.

Figure 5 is a sectional view taken on the line 5—5 of Fig. 3.

Figure 6 is a detail side elevation, partly in section, of the resistance element used with the filament of the heater.

Figure 7 is a diagrammatic view of the wiring for the heater resistance element.

Figure 8 is a diagrammatic view of the wiring for connecting a testing device to the tubes being rejuvenated.

Referring to the drawings, the numeral 10 designates a chassis of suitable construction which is provided with a flat top wall 11. The top 11 is provided in substantially the center thereof with an elongated longitudinally extending slot or opening 13 in which a slide 12 is mounted, the slide 12 having longitudinal flanges 14 which support the slide 12 on the top 11 for sliding movement. Opposed guides 15 are disposed on opposite sides of the opening 13 and are secured to the top 11 by means of screws 16 or like fastening elements.

The slide 12 has a plurality of sockets 17 secured thereto, these sockets being adapted to

receive the prongs of tubes of various types, and it will be understood that as many sockets 17 may be provided as may be considered desirable.

A tube heating means, generally designated at 18 is supported in a position overlying the center of the opening 13. The heating means 18 is secured in suspended relation to a supporting means 19 by means of headed pins 20, and this supporting means 19 comprises a pair of elongated bars 21 which are provided with intermediate opposed offset portions 22 in which the heating means is loosely disposed, the bars 21 being secured together by means of rivets 23 or like fastening means.

The supporting member 19 is held in the desired operative position between a pair of vertically disposed standards 24 and 25. The standard 24 comprises a pair of vertically disposed spaced apart bars 26 provided with right angle base portions 27 which are secured by fastening means 28 to the top 11. The bars 26 have a plurality of vertically spaced apart openings 29 through which a pin 30 is adapted to engage, the pin 30 also extending through an end of the supporting member 19.

The standard 25 comprises a pair of vertically disposed spaced apart bars 31 provided with right angle base portions 32 which are secured by fastening means 33 to the top 11. The bars 31 are provided with a plurality of vertically spaced apart openings 34 through which a pin 35 engages, the pin 35 also extending through an opening 36 provided in the supporting member 19.

The heating member 18 comprises inner and outer cylindrical members 37 and 38, respectively, which are open at each end, and a resistance coil 39 is disposed in the space between these members 37 and 38. An insulating means 40 is interposed between the coil 39 and the periphery of the inner casing member 37, and the space between the coil 39 and the outer casing member 38 is filled with asbestos 41 or a like heat resisting means.

The heat generated by the heating member 18 is controlled by means of a controlling member, generally designated as 42. The controlling member 42 comprises a resistance coil 43 which is mounted on a porcelain body 44 having a threaded lower end portion 45 which is adapted to be threaded into a socket 46 having contacts 47 and 48. The contact 48 has a conductor 49 connected thereto, and this conductor 49 is adapted to be connected to a suitable source of electric current supply of desired capacity. The contact 47 is connected by means of a conductor 50

- 50 to one side of the heater element 18, and the other side of the heater element 18 is connected by means of a conductor 51 to the other side of the source of current supply.
- 5 A switch 52 is interposed in the conductor 49, and a second switch 53 is interposed in a conductor 54 which is tapped into substantially the center of the coil 39, the conductor 54 being connected to one side of the electric current supply.
- 10 A third switch 55 is interposed in a conductor 56 which is connected to the conductor 50 which is in turn connected to the source of current supply so that when the switch 55 is closed and the switches 52 and 53 are open the heating coil 39 is connected directly to the source of current supply.

In Figure 8 there is disclosed the wiring diagram by means of which the sockets 17 may be connected through a cable 57 having an adaptor 20 plug 58 secured thereto to a suitable testing device (not shown). The cable 57 includes the usual filament conductors 59 and 60, and such other conductors 61, 62, 63, and 64 as are necessary to connect the different sockets 17 with complementary sockets or the like carried by the testing device.

The heat controlling member 42 may be enclosed in a casing 65 which is mounted on the top 11, and the member 42 with the casing 65 are preferably mounted adjacent one corner of the top 11, as shown in Fig. 2.

In the use and operation of this device, the desired tube is mounted in a selected socket 17, and where such tube is provided with a terminal 35 66, a conductor 67 may be connected thereto, the conductor 67 being supported in dependent relation by means of a tubular supporting member 68 of L-shaped construction which has one end thereof secured to the top 11. With the tube T 40 mounted in the selected socket 17, the switch 52 may be closed so as to provide the lowest temperature for the heating member 18. The heating member 18 is then lowered so as to engage about the tube T, as shown in Figs. 1, 3, 4, 45 and 5. The correct height of the heating member 18 may be obtained by means of the removable pins 30 and 35. The plug 58 may then be connected to a suitable testing device (not shown) so that the quality of the different elements with 50 in the tube T may be determined during the baking process. The temperature of the heating member 18 may be controlled by means of closing the selected switch connected to the coil of the control member 42.

55 This baking process will also have the effect of volatilizing any magnesium which is deposited on the inside of the tube on the silver or mercury coating of the tube, so that any excess gases caused by the treatment of the tube will be 60 absorbed in the same manner as such gases were absorbed during the original treatment thereof.

The hereinbefore described method and means for rejuvenating radio tubes has been placed in

actual practice, and tubes treated thereby have been found to operate in their original manner, and such rejuvenated tubes will operate satisfactorily for a considerable length of time.

It is obvious that various changes and modifications may be made in the details of construction and design of the above specifically described embodiment of this invention without departing from the spirit thereof, such changes and modifications being restricted only by the scope of the 10 following claims:—

What is claimed is:

1. A tube rejuvenating means comprising a base, a tube socket carried by the base, a tube heating member, means for supporting said heating member above said tube socket and about a tube in said socket, means for connecting said heating member to a source of electric current supply, and means for controlling the heat generated by said member. 20

2. A tube rejuvenating means comprising a base, a tube socket carried by the base, a tube heating member, means for supporting said heating member above said tube socket and about a tube in said socket, means for connecting said heating member to a source of electric current supply, a resistance coil interposed in said connecting means, and means for mounting said coil on the base. 25

3. A tube rejuvenating means comprising a base, a plurality of tube sockets, a slide member carried by the base, said sockets being mounted on said slide member, a testing device, means for connecting said sockets to the testing device, a tube heating member, means for supporting said heating member about a tube disposed in a selected socket, and means for controlling the heat generated by said heating member. 30

4. A tube rejuvenating means comprising a base, a socket on the base, a pair of uprights disposed on the base, one on each side of said socket, a tube heating member, and means engaging the heating member and the uprights for supporting the heating member about a tube in said socket. 40

5. A tube rejuvenating means comprising a base, a socket on the base, a pair of uprights disposed on the base one on each side of said socket, a tube heating member, and means for releasably securing said tube heating member in 50 dependent relation between said uprights.

6. A tube rejuvenating means comprising a base, a socket on the base, a pair of uprights disposed on the base one on each side of said socket, a tube heating member, an elongated supporting member for said heating member provided with a bowed intermediate portion, means for securing the heating member in said bowed portion, and means for securing said supporting member to said uprights. 55
